United States Patent Office

Des. 188,773
Patented Sept. 6, 1960

188,773

FOLDING TRANSPARENCY VIEWER

Mary C. Thoburn, Troy, N.Y., assignor to Eastman
Kodak Company, Rochester, N.Y., a corporation of
New Jersey

Filed Oct. 28, 1959, Ser. No. 58,104

Term of patent 7 years

(Cl. D61—1)

Fig. 1

Fig. 2

Fig. 3

Fig. 5

Fig. 4

Fig. 6

Fig. 1 is a front perspective view of a folding transparency viewer showing my new design and shown in an open or unfolded position;

Fig. 2 is a top plan view thereof and showing the rear lens folded down;

Fig. 3 is a front elevational view thereof and shown in a folded position;

Fig. 4 is a rear elevational view thereof;

Fig. 5 is a side elevational view thereof; and

Fig. 6 is a top plan view thereof.

Portions of the drawing figures are diagonally lined to indicate transparency.

I claim:

The ornamental design for a folding transparency viewer, as shown and described.
